UNITED STATES PATENT OFFICE.

JAKOB STEIGER, OF EBNAT-KAPPEL, SWITZERLAND.

ROLLER-SKATE.

1,314,159.

Specification of Letters Patent. Patented Aug. 26, 1919.

Application filed June 25, 1918. Serial No. 241,885.

To all whom it may concern:

Be it known that I, JAKOB STEIGER, a citizen of the Republic of Switzerland, residing at Ebnat-Kappel, Switzerland, have invented certain new and useful Improvements in Roller-Skates; and I do hereby declare the following to be a clear, full, and exact description of the invention, such as will enable others skilled in the art to which it applies to make and use the same, reference being had to the accompanying drawing, and to letters or figures of reference marked thereon, which form a part of this specification.

This invention relates to improvements in roller skates provided with two wheels only, arranged one in front of the other and having a pivotally mounted front guide wheel or roller.

A drawback which permits a more general use of the roller skates provided with two wheels only, consists in that such skates can not be accommodated at all, or only in an insufficient manner, to the curve to be described. This disadvantage will be found, for instance, in all roller skates provided with a guide wheel adapted to be swiveled or rotated about a vertical axis.

I am aware, that it has already been proposed to provide on roller skates an adjustable front guide wheel adapted to be rotated about a vertical axis in order to enable skaters to curve about. Said axis lies, however, behind the axis of the front guide

wheel, so that a skate of such design can not be used because the slewing or rotation axis of the guide roller or wheel cuts the line on which the skate is running behind the point of contact of the guide roller with the running surface. In consequence of this, the guide wheel is turned in the wrong direction when describing curves, so that the running wheel has the tendency to deviate the skate from the curve to be described and to force it to move along a line curved in the opposite direction.

The object of the present invention is now to provide a roller skate provided with only two wheels or rollers, the front one of which is mounted on an inclined slewing or rotation axis, in which an accommodation or adjustment of the roller skate to the curve to

be described is possible without the description of the curve being rendered, in consequence of such an adjustment, more insecure. According to this invention, the single front wheel is arranged in such a manner with regard to the slewing or rotation axis inclined from the tip of the skate backward that the point of contact of said front guide wheel with the running surface lies behind the point at which the rotation axis cuts the line to be described, so that the guide wheel remains, notwithstanding the inclination taken up by the skate when turning in curves, nearly vertical to the line to be described and is consequently forced to follow the line to be described. Owing to the fact, that the guide wheel remains approximately vertical to the line to be described, any sliding of the guide roller out of the curve to be described is prevented.

For the purpose of causing the front guide roller to take up a vertical position before the skate is put on the surface on which the skate will then run, I may fix a weight to the slewing or rotation axis causing the guide roller to adjust itself to the line to be described also in that case in which the skate, while taking up a laterally inclined position, is moved toward the line to be described. Because of this, the guide roller will be always in a vertical position when it comes in contact with the running surface, so that it does not matter which position is taken up by the skate when it comes in contact with said surface.

The invention will now be more particularly described with reference to the accompanying drawing illustrating by way of example two embodiments of the invention. In this drawing:

Figure 1 is a front view of the first embodiment;

Fig. 2 is a corresponding side view and Fig. 3 a corresponding plan view.

Fig. 4 is a side view of the front portion of the second embodiment.

Referring to Figs. 1-3 of the drawing, 1, 2 indicate the plate of the skate on which the foot comes to rest; said plate is provided with means for fastening the skate to the shoe. Near the rear end of the skate a running wheel 3 having a rounded off running

surface is supported in a leg 4 fixed to the plate 1, 2. To the front end of the plate 1, 2 is secured by means of screws 5 provided near the front edge of the plate 1, 2 a plate 6 forming a part of a bearing 7. In the latter is revolvably mounted by means of a pivot 8 a fork 9. The fork 9 is provided with slots 10 which act as bearings for the front guide wheel 11. The running surface 10 of the latter is also rounded off. The guide wheel 11 is mounted revolvably in a sleeve 12 through which passes a bolt 13. The end surfaces of the sleeve 12 rest against the legs of the fork 9. The bolt 13 passing through 15 the slots 10 is provided at one end with a head and carries at the other end a nut 14. Upon a tightening of the nut 14, the sleeve 12 is clamped in the fork 9 so that the axis of rotation of the guide wheel 11 is kept in 20 determinate position with regard to the fork 9. The latter is of such a shape that the point of contact A of the roller 11 with the surface on which the skate is running, lies behind the point B at which the prolongation 25 of the axis of rotation of the fork 9 cuts the line to be described, said axis being approximately tangent to the periphery of the roller 11. Owing to this more backward arrangement of the guide wheel 11, an 30 automatic steering of said wheel 11 is attained in the manner already referred to when turning curves.

A spring 15 fixed at one end to an ear-like projection 16 of the plate 1, 2 and at 35 the other end to a hook 17 provided on the fork 9 has the tendency to move the latter always into its middle position. The inclination of the plate 6 is such, that the axis of the fork 9 is inclined at an angle of about 40 45° to the line to be described. The inclination of the plate 6 may be adapted, however, to the requirements of the skater. To this end, screws 18 are screwed into the plate 6, said screws bearing against the bottom surface 45 of the part 1 of the plate 1, 2. Said part 1 is also provided with holes through which pass screws 19 screwed into the plate 6. A tightening of the screws 19 has the effect to secure the plate 6 relatively to the plate 1, 2 in a determinate position. Upon 50 a loosening of one set of screws (18 or 19) and upon a tightening of the other set (19 or 18), the inclination of the plate 6 may be changed relatively to the plate 1, 2. 55 Also the distance of the point of contact of the guide roller 11 with the running surface from the rotation axis of the fork 9 may be adapted to the requirements of the skater by adjusting the nut 14. In the embodiment of the invention illustrated in 60 Fig. 4, the spring 15 is replaced by a weight 20 carried by an arm 21. The latter is fixed to an extension 22 of the pivot 8. The object of this construction is to cause the guide

wheel 11 to take up a vertical position when 65 it comes in contact with the running surface, and this even in the case that the skate is then moved in a horizontal or inclined position toward the running surface.

What I claim now as my invention is:

1. In a roller skate, a foot plate, two rollers arranged in front of one another, a member secured to the rear portion of said plate and acting as a bearing for the rear roller, and a member carrying the front roller having its bearing in the front portion of the shoe plate and adapted to rotate about an axis inclined from the tip of the skate backward, the front roller being arranged in such a manner with regard to said axis that its point of contact with the running surface lies behind the point at which said rotation axis cuts the line to be described. 70

2. In a roller skate, a foot plate, two rollers arranged in front of one another, a member secured to the rear portion of said plate and acting as a bearing for the rear roller, a member carrying the front roller having its bearing in the front portion of said plate and adapted to rotate about an axis inclined 75 from the tip of the skate backward, the front roller being arranged in such a manner with regard to said axis that its point of contact with the running surface lies behind the point at which said rotation axis cuts the line to be described. 80

3. In a roller skate, a foot plate, two rollers arranged in front of one another, a member secured to the rear portion of said plate and acting as a bearing for the rear roller, a member carrying the front roller having its bearing in the front portion of said plate and adapted to rotate about an axis inclined 85 from the tip of the skate backward, the front roller being arranged in such a manner with regard to said axis that its point of contact with the running surface lies behind the point at which said rotation axis cuts the line to be described. 90

4. In a roller skate, a foot plate, two rollers arranged in front of one another, a member secured to the rear portion of said plate and acting as a bearing for the rear roller, a member carrying the front roller having its bearing in the front portion of said plate and adapted to rotate about an axis inclined 95 from the tip of the skate backward, the front roller being arranged in such a manner with regard to said axis that its point of contact with the running surface lies behind the point at which said rotation axis cuts the line to be described, and a weight secured to the pivot of said member adapted to rotate about the inclined axis, said weight causing the front roller to assume a vertical position before the skate is put on the running surface and this even in the case that the skate moved toward the running surface takes up an inclined position. 100

5. In a roller skate, a single front roller mounted to swivel on an axis inclined to the plate of the skate and means to adjust the inclination of the axis. 105

6. In a roller skate, a single front roller mounted to swivel on an axis inclined to the plate of the skate, means to adjust the inclination of the axis and means to adjust said roller to and from said axis. 110

7. In a roller skate, a single front roller mounted to swivel on an axis inclined rearwardly approximately 45° , said axis intersecting the skating surface at a point in front of the point where the roller touches said surface. 115

8. In a roller skate, a single front roller mounted to swivel on an axis inclined rearwardly approximately 45° , said axis intersecting 120 the skating surface at a point in front of the point where the roller touches said surface.

9. In a roller skate, a single front roller mounted to swivel on an axis inclined rearwardly approximately 45° , said axis intersecting 125 the skating surface at a point in front of the point where the roller touches said surface.

said surface, means to alter the inclination of said axis and means to adjust the roller to vary the distance between said points.

8. In a roller skate, a single front roller 5 mounted to swivel on an axis inclined to the plate of the skate, and means sufficient to hold said roller in longitudinal position

when not under load, said means being substantially inactive when said roller contacts with the rolling surface. 10

In testimony that I claim the foregoing as my invention, I have signed my name.

JAKOB STEIGER.
